WEIGHT INDICATOR AND ANCHOR FOR LOAD SUSTAINING LINES

Elmer L. Decker, Long Beach, Calif., assignor to Martin-Decker Corporation, Long Beach, Calif., a corporation of Delaware

Application June 28, 1950, Serial No. 170,784

13 Claims. (Cl. 73—143)

This invention relates to apparatus for indicating the weight of loads on cables or other lines and for anchoring such lines, particularly the dead lines of cable hoist systems employed in the drilling of wells.

It is known that apparatus of this character as used in connection with rotary drilling rigs for oil wells comprises a footing on which a snubbing drum is mounted for limited turning movement and wherein a wire line clamp is mounted on an arm extended from the drum to anchor the dead line of the cable system which supports the drill string. A plurality of loops of this line are wound around the drum whereby the line is snubbed to relieve the clamp of the load on the line. When it is desired to feed fresh line into the system the clamp is released and the fresh line is extended into the system from a supply of cable disposed to one side of the clamp. A hydraulic sensing means is connected between the footing and the extended arm of the drum in such manner that responsive to limited turning movement of the drum, said element will operate a weight indicator to measure the load sustained by the lines of the system. While this apparatus is advantageous in that as a simple unit it serves the purposes of weight indication, dead-ending the line and feeding fresh line into the system, it is also objectionable due to the fact that the line must be reeved between the drum and its mounting in the operation of placing a number of windings around the drum, and as the line is quite stiff, this operation is difficult and laborious, and the several complete windings often take a set that is difficult to straighten and in some cases damages or weakens the line.

It is therefore an object of this invention to provide an improved weight indicator and anchor of the character described.

It is another object of this invention to provide a weight indicator and anchor for a load sustaining line, which provide all of the advantages and none of the disadvantages of apparatus of this character as heretofore employed.

It is a further object of this invention to provide apparatus such as described which affords the desired snubbing action and anchoring of the line without requiring that several turns of the line be wound around a drum or wound in complete turns.

It is another object of this invention to provide an improved anchoring means for a load sustaining line in which the clamp for anchoring or dead-ending the line is relieved of objectionable stresses and wherein fresh line free from objectionable twists or bends may be fed through the anchoring means as desired.

It is another object of this invention to provide an apparatus such as described in which a lever instead of drum, having snubbing means thereon, provides for extending the line in a sinuous path in contact with the snubbing means to achieve the desired snubbing action without the 360 degree turns or windings heretofore required.

It is another object of this invention to provide ap-

2

paratus such as described in which the line may be mounted sidewise in the apparatus in contact with the snubbing means without requiring any reeving of the line between parts of the apparatus or the winding of the line in complete turns, thereby avoiding the bending, kinking or twisting which tends to weaken the line or give it a set which is difficult of removal.

It is a further object to provide a weight indicator and line anchor unit such as described wherein the hydraulic sensing element may be adjusted to compensate for change in the number of load-sustaining lines employed.

It is another object of this invention to provide a weight indicator and line anchor wherein the sensing element may be adjusted or removed for inspection, re-loading or repair and replaced without requiring that the blocks be laid down and the drilling operation interrupted.

It is another object to provide apparatus such as described wherein the line is connected with a movable member by being convolved sinuously in one plane, there-

by avoiding objectionable twisting of the line, and difficult winding operations around a drum, as heretofore required, and making the movable member responsive to a straight line pull such that it will be accurately responsive to small increments of weight variation and provide for a greater nicety of weight measurement.

This invention possesses many other advantages and has other objects which may be made more easily apparent from a consideration of several embodiments of the invention. For this purpose there are shown two forms in the drawings accompanying and forming part of the present specification. These forms will now be described in detail, illustrating the general principles of the invention; but it is to be understood that this detailed description is not to be taken in a limiting sense, since the scope of the invention is best defined by the appended claims.

Referring to the drawings:

Figure 1 is a diagrammatic view of apparatus embodying the present invention, as installed on the drill rig frame of a well;

Figure 2 is an enlarged elevational view of the apparatus, with the safety plate removed, and the sensing device in section;

Figure 3 is a top plan view of the apparatus shown in Figure 2, with the safety plate mounted in place thereon;

Figure 4 is a vertical sectional view taken on the line 4—4 of Figure 2;

Figure 5 is an enlarged fragmentary horizontal sectional view taken on the line 5—5 of Figure 2, showing the swiveled line or cable clamp;

Figure 6 is an enlarged sectional view taken on line 6—6 of Figure 2, showing the line or cable clamp;

Figure 7 is a sectional view taken on the line 7—7 of Figure 2;

Figure 8 is a fragmentary front elevation of a modified form of this invention; and

Figure 9 is a sectional view taken on line 9—9 of Figure 8.

As shown in Figure 1, a weight indicating and line anchoring unit 9 embodying the present invention is mounted on the drill rig frame 10 of a well and has anchored thereto the dead line 11 of a cable hoist system as employed in connection with rotary drilling rigs, both of which latter are well known in this art and therefore not illustrated. The dead line 11 is joined to a supply of fresh cable 12 on a spool 13 supported adjacent the apparatus and from which fresh cable may be fed into the system through the apparatus. The apparatus includes a hydraulic sensing means 14 which responds to line loads imparted thereto, for operating a pressure operated weight gauge or indicator 15 of the

type well known in this art, mounted in sight of the driller whereby the weight on the bit may be regulated according to the readings of the indicator in order that a more efficient drilling operation may be carried out.

More specifically, the apparatus comprises relatively movable members 16 and 17 on one of which is mounted a line clamp 18 for dead-ending the dead line 11. Snubbing means 19 is mounted on the other of said members for relieving the load on the clamp, relative movement between the members operating the sensing means 14, which in turn operates the indicator 15.

The member 16 comprises an elongated plate-like body 16a from one end of which extends an integral arm 16b, the body being securely fixed by bolts 20 to an upright member 10a of the drill rig frame 10, whereby member 16 is stationarily mounted with its opposite flat faces substantially vertical.

The member 17, being the movable member, comprises an elongated plate-like body 17a pivoted to the member 16 intermediate its ends so that it constitutes a lever. It is mounted on anti-friction bearings 21 supported on a stub shaft 22 fixed to the member 16a, as shown in Figure 4. An arm 17b as an integral extension of the body 17a of the member 17, is substantially equal in length to the arm 16b and disposed in vertically spaced relation thereto and substantially parallel therewith, the sensing means being connected to and disposed between said arms.

As here shown, the cable or line clamp 18 is mounted on the end of the stationary member 16 opposite the end from which the arm 16b extends. It is swivelled on an extension 24 of the member 16 which projects beyond the adjacent end of the movable member 17 and includes a base block 25 having a swivel pin 26 press fitted or otherwise fixed thereto and mounted in a bearing 27 in the extension 24, being held in place by a suitable retainer ring 28. A clamping block 29 is adjustably and removably mounted on the base block 25 by means of bolts 30. Opposed line embracing jaws 31 are mounted in complementary recesses 32 in the blocks and are forced into clamping engagement with the line upon tightening the bolts 30.

The snubbing means 19 mounted on the body 17a of the movable member or lever 17 is such that the line or cable 11 is extended in a sinuous path, in one plane, and in snubbing contact therewith. This means is on the outer side of the member 17 and of such form that the cable may be positioned sidewise in contact therewith and does not require that the cable be wound therearound or thereon. Thus, this means as here shown comprises a series of arcuate flanges or like elements 33, 34, 35 and 36 which extend laterally outward from the vertical surface of the member 17 in fixed relation thereto so as progressively in the order named, to describe a tortuous or sinuous path for the cable without requiring that any part of the cable in contact therewith form a complete 360° winding or be disposed out of one vertical plane. Thus, from left to right as seen in Figure 2, the cable passes over the upper side of the element 33, thence under and against element 34 and around and over the right end of the latter and back and around the arcuate element 35, which is concentric with the axis of the member 17, then around element 36 and up to the crown block (not shown) of the hoist system. The lineal surfaces of these snubbing elements are of such extent and arrangement that in its contact therewith in a sinuous path, the cable is not kinked or twisted or coiled in a manner comparable to that where it is wound several times around a drum. The combined action of these elements is such that an effective snubbing takes place to relieve the cable anchor 18 of strains and to make possible a limited movement of the member 17 responsive to loads imposed thereon by the line 11. The cable contacting surfaces of the elements 33, 34, 35 and 36 are grooved to retain the cable thereon. However, a safety

plate 37 is removably secured by means of fastenings 38 to the member 17 so as to overlie the snubbing element and cable thereon, thus assuring that the cable will be retained on said elements, as shown in Figure 3.

It should be noted that the cable leads in a straight line from the clamp 18 in line with the axis of the movable member 17 until it encounters the first of the snubbing elements 33, which latter guides the cable below and forwardly of said axis thence upward and back toward the axis where the next element 35 carries the cable up and around the axis but not completely there-around. The cable then extends forwardly and above said axis in an arcuate path around the element 36 whence it leaves the upper end of element 36 in extending in a straight line to the crown block.

Responsive to the load pull on the line 11, the movable member 17 will rock on its axis so that the arm 17b will be raised relative to the arm 16b while the other end of the member 17 will be lowered. In this connection, it should be noted that the pivotal mounting of the cable clamp 18 permits the clamp to turn to prevent sharp bending of the cable adjacent the clamp when the member 17 is rocked relative to the clamp as above noted. However, this relative movement between the members 16 and 17 is comparatively small, being so limited by the sensing element 14.

Means are provided, as best shown in Figures 2 and 7, for additionally limiting relative movement between the arms 16 and 17, particularly so that the sensing element 14 may be adjusted or removed and replaced without lowering the blocks and interrupting the drilling operation. This means includes a link 39 straddling the arms 16b and 17b, with its other end closed below the arm 16b by suitable means, for example, a spacer block 41 held in place by bolts 42. A screw 43 is adjustable in the block 41 and normally spaced below the arm 16b sufficiently to permit of relative movement between the arms 17b and 16b for proper operation of the sensing element 14, such relative movement being preferably limited by the sensing element rather than link 39. However, this screw may be adjusted so that it will contact arm 16b and prevent movement between arms 16b and 17b whereby the sensing element 14 may be adjusted, removed and replaced without requiring that the load be taken off the dead line 11, or the drilling operation interrupted. Furthermore, if the sensing element 14 is removed without adjusting the screw from its normal position, the screw will contact arm 16b with but a small upward movement of the arm 17b as caused by the load on the line 11, since the normal spacing of the screw from the arm 16b is very slight due to the sensing element being fully operable with a small movement of the arm 17b. However, in most cases it is desirable to relieve the load on the sensing element for adjusting, removing, and replacing it, thus this screw and its associated parts serve as a means by which the arm 17 may be lowered, that is swung downward, while the dead line load is carried thereby, and so held to relieve the load on the sensing element to facilitate adjustment, removal and replacement of the sensing element, as will be hereinafter more fully described.

The arms 16b and 17b are comparatively long and the arm 16b is offset at 16c as shown in Figure 3 so as to vertically align with arm 17b and to accommodate proper installation of the sensing element 14 between said arms.

As shown in Figure 2, the sensing element 14 comprises a hydraulic cylinder 44 and a piston 45, the cylinder being connected with the stationary arm 16b by means of a link 46 while the piston rod 47 or piston 45 is connected by means of a similar link 48 with the movable arm 17b. A hydraulic line 49 leads from the top of the cylinder 44 to the hydraulically operated indicator 15. This line with the cylinder 44 and indicator 15 forms a closed hydraulic system wherein the cylinder and piston are initially installed between the arms 16b and 17b in such manner as to permit of limited movement of arm 17b

according to the setting of the stop link 39 and the stroke of the piston 45 for example, as indicated in Figure 2. Thus, as the movable arm 17b is raised relative to the stationary arm 16b responsive to the pull of the cable on the movable member 17 and consequent rocking of the latter on its axis, the piston 45 is lifted relative to the cylinder 44 and fluid displaced from cylinder 44 becomes effective in the indicator 15 to measure the load on the line 11.

The arms 16b and 17b with the links 46 and 48 provide a means for adjusting the sensing element longitudinally of the arms, there being companion notches 50 and 51 at longitudinally spaced points in the arms 16b and 17b respectively for accommodating removable pins or bolts 52 and 53 in the respective links, to hold the sensing means in adjusted positions. This adjustment is effected in accordance with the number of lines operating from the travelling block in the hoisting system, the sensing element being moved toward the outer ends of the arms with a reduction of the number of lines and inwardly from said outer ends with an increase of lines.

It is important to note that the sensing element may be adjusted, or removed for reloading, inspection or repair and replaced without lowering the blocks or interrupting the drilling operation, the dead line load being maintained on the movable members 17 all the while. The screw 43 when turned by means of a suitable tool, not shown, so as to contact the arm 16b and move the arm 17b toward arm 16b makes it possible to adjust the sensing element as desired along the arms 17b and 16b or to remove and replace the sensing element without interrupting the drilling operation. The screw may be readily retracted to normal position shown in Figures 2 and 7, after the sensing element is adjusted or replaced, thereby restoring the apparatus for weight indicating operation.

It should be noted that in accordance with this invention the line 11 is sinuously convolved in one vertical plane. In other words, the line, in contacting the reversely curved snubbing elements 33, 34, 35 and 36, is formed into a series of reversely curved loops, with opposite sides of the portion of the line forming the loops, frictionally engaged by the snubbing elements. This makes it unnecessary to twist or kink the line and provides for an easy application thereof to the snubbing elements on the movable member 17. This arrangement also provides for a straight line pull on the movable members and an accurate response to small increments of load variation, thus affording a nicety of weight indication. Moreover, in making the snubbing convolutions of the line in one plane, the bulk of the apparatus is reduced and the construction thereof simplified compared to the drum-type apparatus heretofore provided.

The apparatus hereof without the indicating means will serve as an efficient cable anchor with provisions for relieving the cable clamp from objectionable stresses and for feeding into the system as desired fresh cable which is free from objectionable twists or bends.

As shown in Figures 8 and 9, a modified form of this invention provides for mounting a releasable line or cable clamp 55 on the movable member 17 instead of on the stationary member 16. This clamp is similar to the clamp 18 but is fixed to an extension 56 on the movable member 17 instead of being pivoted, inasmuch as movement of the clamp with the member 17 precludes the necessity of pivotally mounting it. With the exception of providing the extension 56 on the member 17 instead of on the member 16, and fixing the clamp to extension 56, this modified form of the invention is of the same construction and arrangement as the form of the invention shown in Figures 1 and 6 inclusive.

I claim:

1. In a weight indicator and anchor for a load sustaining line, the combination of; a stationary member, a member mounted thereon for pivotal movement with re-

spect thereto, means on said pivoted member forming reversely curved surfaces for contact with said line throughout a sinuous path, a clamp for dead-ending said line on said stationary member, and relative motion resisting weight indicating means interconnected between said members for operation responsive to relative movement thereof.

2. In a weight indicator and anchor for a load-sustaining line, the combination of; a stationary member, a

10 member mounted thereon for pivotal movement with respect thereto, means on said pivoted member forming reversely curved surfaces for contact with said line throughout a sinuous path, a clamp pivoted on said stationary member, operable for releasably anchoring the line and to turn on its pivot responsive to pivotal movement of said pivoted member, and relative motion resisting weight indicating means interconnected between said members and operating responsive to relative movement between said members.

15 20 30 3. A weight indicator and anchor for a load sustaining line comprising in combination: a stationary member, a relatively movable member, means on one of said members for contacting and snubbing the line throughout a sinuous path to cause relative movement of the members responsive to pull on the line, means for releasably clamping said line, means mounting said clamping means on one of said members for movement relative thereto responsive to relative movement between said members, and relative motion resisting weight indicating means interconnected between said members responsive to relative movement of said members.

4. In a weight indicator and anchor for a load-sustaining line, the combination of; a stationary member, a movable member pivoted on the stationary member with 25 35 a surface thereof vertically disposed, a plurality of arcuate elements extending laterally outward from said surface and forming surfaces in a sinuous path for contacting opposite sides of the line and snubbing the line, means for releasably anchoring the cable to one of said members and means for attaching a relative motion resisting weight indicator between said members for operation responsive to relative pivotal movement of said movable member with respect to said stationary member.

45 5. In a weight indicator and anchor for a load-sustaining line, the combination of; a stationary member, a movable member pivoted on the stationary member with a surface thereof vertically disposed, a plurality of arcuate elements extending laterally outward from said surface and forming surfaces in a sinuous path for contacting opposite sides of the line and snubbing the line, means for releasably anchoring the cable to one of said members, means for attaching a relative motion resisting weight indicator between said members for operation responsive to relative pivotal movement of said movable member with respect to said stationary member, and means mounted on said movable member and overlying said arcuate elements to retain the line in contact therewith along said path.

6. A weight indicator and anchor for a load sustaining 60 line comprising in combination: a stationary member, a relatively movable member, means for anchoring the line to one of said members; means on one of said members forwardly of said anchoring means for contacting opposite sides of the line and snubbing the line and causing relative movement between said members responsive to the pull on said line, relative motion resisting means interconnected between said members operating in response to relative movement thereof to indicate the pull on said line, and means interconnected between said members 65 70 operative at will to effect relative movement between said members.

7. A weight indicator and anchor for a load sustaining line comprising in combination: a stationary member, a relatively movable member, means for anchoring the line to one of said members; means forwardly of said anchor-

ing means on one of said members forming reversely curved surfaces for contacting opposite sides of the line and snubbing the line and causing relative movement between said members responsive to the pull on said line, relative motion resisting means interconnected between said members operating in response to relative movement thereof to indicate the pull on said line, and means interconnected between said members operative at will to effect relative movement between said members in a direction opposite that caused by the pull on the line.

8. In a weight indicator and anchor for a load-sustaining line; the combination of a stationary member including an axis; a movable member mounted for relative movement about said axis; an arm carried by each of said members extending outwardly from said axis; means for anchoring the line to one of said members; means on one of said members against which the line is engageable in the form of a plurality of reversely curved loops for effecting a snubbing action on the line and relative movement between said members responsive to the pull on the line; and relative motion resisting weight indicating means connected between said arms for operation responsive to relative movement of said members.

9. In a weight indicator and anchor for a load-sustaining line; the combination of a stationary member including an axis; a movable member mounted for relative movement about said axis; an arm carried by each of said members extending outwardly from said axis; means on one of said members for anchoring the line thereto; reversely curved elements on one of said members against which opposite sides of the line are engageable to effect a snubbing action on the line and relative movement between said members responsive to the pull on the line; relative motion resisting weight indicating means connected between said arms for operation responsive to relative movement of said members; and means affording the connection of said indicating means to said arms at points variously spaced from said axis.

10. In a weight indicator and anchor for a load-sustaining line; the combination of a stationary member including an axis; a movable member mounted for relative movement about said axis; an arm carried by each of said members extending outwardly from said axis; means for anchoring the line to one of said members; means on one of said members against which the line is engageable to effect a snubbing action on the line and relative movement between said members responsive to the pull on the line; relative motion resisting weight indicating means connected between said arms for operation responsive to relative movement of said members; a link pivoted to one of said arms; and a member on said link adapted to engage the other of said arms to limit relative movement between said arms.

11. In a weight indicator and anchor for a load-sustaining line; the combination of a stationary member including an axis; a movable member mounted for relative movement about said axis; an arm carried by each

5 of said members extending outwardly from said axis; means on one of said members for anchoring the line thereto; means on one of said members against which the line is engageable to effect a snubbing action on the line and relative movement between said members responsive to the pull on the line; relative motion resisting weight indicating means connected between said arms for operation responsive to relative movement of said members; a link pivoted to one of said arms; and an adjustable member on said link operable against the other of said arms for effecting relative movement between said arms in a direction opposite that caused by the line pull.

10 12. In a weight indicator and anchor for a load-sustaining line; the combination of a stationary member including an axis; a movable member mounted for relative movement about said axis; an arm carried by each of said members extending outwardly from said axis; means on one of said members for anchoring the line thereto; elements on one of said members variously spaced from said axis and against which the line is engageable to effect a snubbing action on the line and relative movement between said members responsive to the pull on the line; relative motion resisting weight indicating means connected between said arms for operation responsive to relative movement of said members; means affording the connection of said indicating means to said arms at points variously spaced from said axis; and means connected with said arms including a member adjustable for effecting relative movement between said arms in a direction opposite that caused by the line pull.

15 13. In a weight indicator and anchor for a load-sustaining line; the combination of a stationary member; a movable member pivoted on the stationary member; said movable member having a surface substantially perpendicular to the pivotal axis thereof; a plurality of arcuate elements extending outwardly from said surface and providing snubbing surfaces in a sinuous path for contacting opposite sides of the line; means releasably anchoring the line to one of said members; and means providing for the attachment of a relative motion resisting weight indicator between said members for operation responsive to pivotal movement of said movable member with respect to said stationary member.
